UNITED STATES PATENT OFFICE.

JOSEPH L. McCCLANE, OF DAYTON, OHIO, ASSIGNOR TO DAYTON-WRIGHT COMPANY, OF DAYTON, OHIO, A CORPORATION OF DELAWARE.

RETRACTABLE RADIATOR.

Application filed February 14, 1922. Serial No. 536,540.

To all whom it may concern:

Be it known that I, JOSEPH L. McCCLANE, a citizen of the United States of America, residing at Dayton, county of Montgomery, 5 and State of Ohio, have invented certain new and useful Improvements in Retractable Radiators, of which the following is a full, clear, and exact description.

This invention relates to airplane radiators and has special reference to means for varying the cooling effect thereof by exposing more or less of the radiator area to the cooling air blast.

One of the objects of this invention is 10 to provide a retractable radiator which is moved in such a manner as to at all times maintain the same direction of the blast upon the cooling area. Thus the greatest amount of cooling for the head resistance 20 offered is always obtained.

Another object is to provide a form of retractable radiator which is movable horizontally and thus greatly reduce the work required to operate the same since no weight 25 must be raised or lowered in operating the radiator.

Another object is to provide a simple and 30 absolutely positive drive for moving the radiator either outwardly or inwardly.

Further objects and advantages of the present invention will be apparent from the following description, reference being had to the accompanying drawings, wherein preferred forms of embodiments of the present 35 invention are clearly shown.

In the drawings:

Fig. 1 is a phantom view showing the general location in the airplane of the radiator and operating means therefor.

Fig. 2 is a similar view transverse the airplane and showing the retracted position of the radiator in dotted lines.

Fig. 3 is a view similar to Fig. 2 but on a large scale to show the details of construction.

Fig. 4 is a view similar to Fig. 1 but on a large scale to show the details of construction.

Fig. 5 is an enlarged view taken on line 50 5—5 of Fig. 4.

Fig. 6 is a view taken at right angles to Fig. 5.

Fig. 7 is a plan detail view of the normal operating means and gearing.

55 Similar reference characters refer to sim-

ilar parts throughout the several views.

In this embodiment of the invention I have shown the airplane body or fuselage having the frame members 11 and 12, 11 being one of the longérons and 12 a transverse bulkhead located behind the engine. The weight of the radiator 15 is carried by these frame members, the greater part of this weight being taken directly by the bulkhead 12. This bulkhead 60 is provided with a plurality of rollers 16 which have pivots supported thereupon in any suitable manner. Directly opposite to the rollers 16 are similar rollers 17 whose pivots are supported in a frame 13 which 65 in turn is supported upon the frame members of the fuselage (see Fig. 4).

The radiator 15 is built upon a slidable frame 20 which comprises four channel members 21 braced together to form a rigid 75 structure. This frame 20 is slidable along the rollers 16 and 17 which track in the guide channels 21 as clearly illustrated. The frame is made sufficiently wide so that when the radiator 15 is fully exposed or 80 extended outside the contour 10 of the fuselage its weight is supported by cantilever action by the other side of frame 20 still in contact with rollers 16 and 17. Fig. 3 illustrates in full lines the most extended 85 position of the radiator and in dotted lines the fully retracted position thereof.

The means for operating the radiator will now be described. Rigidly secured to the frame 20 by any suitable means is the toothed 90 rack 25 which is driven by a pinion 26 keyed upon the end of drive shaft 27. Drive shaft 27 extends to the operator's cock pit and is provided with means for manual operation by the pilot. In the drawings I have 95 shown the drive shaft 27 extending closely along the side of the fuselage and supported from the longeron 11 at the operator's cock pit and there provided with bevel gears 28 and 29 and hand wheel 30. It comes 100 within the scope of my invention to operate drive shaft 27 by any other form of gearing or cranking means and I do not wish to be limited to the form shown.

By means of the toothed rack and pinion 105 drive for retracting or extending the radiator an absolutely positive movement is obtained in either direction and independent of gravity or wind pressure to assist or hinder the movement. Since it is not neces-

sary to raise the weight of the radiator and water therein or to overcome wind pressure in either retracting or extending the radiator the force required for the operation is comparatively small. However, in a modified form of this invention the radiator may have a vertical movement, in which event gravity would assist the movement in one direction and oppose it in the other. 10 The other advantages of the invention would remain the same.

An important advantage of my invention resides in the movement of the radiator parallel to itself which causes the air blast 15 to strike it at the same angle in whatever position it may have. Thus it may be set at its most efficient angle for cooling and for head resistance and it will always retain that angle regardless of the position 20 to which it may be retracted or extended.

While the forms of mechanisms herein shown and described constitute preferred forms of embodiments of the present invention, it is to be understood that other 25 forms might be adopted, all coming within the scope of the claims which follow.

What I claim is as follows:

1. In an airplane having a body, a radiator having a rigid member attached thereto, 30 said member acting as a cantilever to support said radiator and extending laterally from the side of the body, and means operable during flight for sliding the radiator together with said rigid lateral support laterally inwardly.

2. In an airplane having a substantially

streamlined body, an aperture in the side wall of said body, a radiator movable into and out of the body through said aperture, and a stationary support for said radiator 40 entirely within the contour of said streamlined body, said radiator having a lateral extension rigid therewith and cooperating with said stationary support for supporting the weight of said radiator when in extended 45 position.

3. In an airplane having a body, a radiator located at the side of the airplane body, said radiator having a rigid frame secured thereto and projecting within said body 50 whereby the weight of said radiator is supported as a cantilever, and means for moving said radiator laterally into the contour of the body.

4. In an airplane having a substantially 55 streamlined body, an aperture in the side wall of said body, substantially at the point of its greatest width, a radiator movable into and out of the body through said aperture, and a stationary support for said radiator entirely within the contour of said 60 streamlined body, said radiator having a rigid lateral extension cooperating with said stationary support for supporting the weight 65 of said radiator when in extended position.

In testimony whereof I hereto affix my signature.

JOSEPH L. McCLANE.
